UNITED STATES PATENT OFFICE

ARTHUR C. BADGER, OF NEWTON, MASSACHUSETTS

FIRE EXTINGUISHER

Application filed March 16, 1927. Serial No. 175,738.

This invention relates to fire extinguishers of the type in which two reagents, kept apart before the time of use, are caused to mingle by inverting the extinguisher and to generate gas by their reaction; such gas exerting pressure upon the liquid, which also is contained in the extinguisher, to expel such liquid forcibly. One of the particular purposes of the invention is to provide means by which the reagents, contained in separate solutions, may be intimately mixed in a uniform and progressive manner in course of being discharged, to the end that the liquid when discharged will have a foamy consistency with near uniformity in the size of the bubbles. Thus, other things being equal, the foam delivered from the extinguisher is more lasting and effective than one in which the mixture of gas and liquid is less diffused and intimate and there is greater disparity in the sizes of the gas bubbles imprisoned in the liquid. In the accomplishment of this object, I have devised the novel inventions and improvements, the preferred embodiments of which are described in detail in the following specification. These novel features comprise means for guiding the solutions from separate containers or spaces within the extinguisher into distributed union adjacent to the outlet, and for transferring a portion of the gas evolved by reaction of the chemical compounds into the space which is then above the main body of liquid, without mixing with the liquid.

While I have thus indicated one of the objects of the invention as concerned with the formation and delivery of foam from a fire extinguisher, I am not restricted as to that mode of use, but claim all novel features of the device for all purposes and modes of use to which they may be adapted.

In the drawings,—

Fig. 1 is a vertical sectional view of a fire extinguisher embodying the present inven-

tion, shown in the inactive position, but ready to be inverted and put to use;

Fig. 2 is a fragmentary cross section on line 2—2 of Fig. 1;

Fig. 3 is a fragmentary view of the upper 50 end of the upright extinguisher, showing the casing or shell in section and the interior parts in elevation.

Like reference characters designate the same parts wherever they occur in all the figures.

The reference character 1 designates the shell or casing of the extinguisher which may be of any size and capacity, and of any shape suitable for fire extinguisher use. That is, it may be small enough to be carried and operated in the hands of a person, or so large as to require mounting on a wheeled truck. The one here shown is provided at one end with a base 2 by which it may be 60 stably supported on a floor, and at the other end with a mouth ring 3, on which a cap or cover 4 is detachably threaded. The materials and method of construction of such shell may be of any character usual in the art or 70 suitable for the purpose.

An inner receptacle 5 is placed within the container. This receptacle has a closed bottom 6, and is open at the opposite end, being there provided with an external lip 7 adapted 75 to rest and be supported on a ledge 8 within the mouth ring 3. An internal lip 9 is formed within the receptacle near its open end, but at some distance inward therefrom. The inner edge of the lip 9 defines an opening which 80 is preferably cylindrical, and in which is located a stopper having a cylindrical skirt portion 10 which fits slidably within the rim of the lip 9, a flange 11 overlapping such lip and adapted to be closed against it, and a 85 central tapered projection 12. A stem 13, which projects through a stuffing box 14 in the cap or cover 4, and is in threaded engagement with a sleeve portion 15 of said cap, has a flanged head 16 in swiveled connection with 90

the upper end of the stopper, through the agency of a retaining ring 17 screwed into the stopper as shown, or by other suitable means. Ports 18 are formed in the stopper 5 skirt for outlet of the contents of the receptacle 5. Preferably these ports are small in size and large in number, all distinct from one another, and arranged in two or more zones surrounding the axis of the stopper. 10 Thus a subdivision into a large number of streams of the solution running from the receptacle is effected, and a more or less rapid emptying of the receptacle is permitted according as the stopper is opened more or less 15 widely. By operation of the stem 13, the stopper may be moved inward until the ports 18 are within the lip 9 and the flange 11 is closed against the lip, thereby preventing outflow of the contents of the receptacle, or it 20 may be moved outward, as shown in the drawings, until the ports 18 are brought to a greater or less extent beyond the lip 9.

The projection 12 of the stopper, previously mentioned, extends inward or downward centrally 25 from the upper end wall of the stopper and is provided and formed in such manner as to deflect and spread the liquid flowing from the inner receptacle, when the extinguisher is inverted, outwardly in all directions. To this end it is tapered and its sides 30 are longitudinally curved, and join the end of the stopper on lines which, in all radial planes of the stopper, conform substantially or in a general way to lines of stream flow. Considering 35 the surface of this projection and the adjoining inner or under surface of the end wall of the stopper as a curve of revolution, the elements of such surface are concave lines of smooth curvature and having different 40 radii of curvature in different parts. The part of the curve at the tip of the projection has the longest radius, and from there toward the rim or flange 11 of the stopper the radii of successive parts of the curve become 45 progressively shorter; but even at the upper end of the curve, where it meets the rim, the radius is so long that the center of curvature is at least, or substantially, as far away from the axis of the stopper as the rim. By 50 reason of such curvature, the surface of the stopper which is directed toward the outflowing liquid deflects the liquid smoothly and gradually toward the outlet ports 18, without tendency to cause a reversal in the direction 55 of flow.

In the sides of the inner receptacle between the lip 9 and the open end, are ports 19 which give communication between the interior of the receptacle and the outer space 60 within the main casing.

An annular partition or diaphragm 20 is fitted and secured within the main or outer casing near the upper end thereof, and is provided with a flange or web 21 rising from 65 its inner circumference and surrounding the

inner receptacle, but separated therefrom by an annular space 22 of such width as to limit the rate of flow of the liquid contained in the extinguisher outside of the inner receptacle, while permitting a sufficiently free flow 70 thereof. Such web or flange extends toward the mouth of the casing, but terminates short of the end wall thereof and of the mouth ring by a distance sufficient to permit free flow of the mingled solutions, except at the side 75 where the outlet is located, and there it extends all the way, or approximately so, to the mouth ring. At all points, however, the web 21 preferably extends beyond the zone 80 at which the lip 9 joins the side walls of the inner receptacle, and approximately as far as the plane in which the rim of such lip 9 is located, said lip being preferably inclined substantially as shown in the drawings.

The outlet is at 23 and is provided by a 85 suitable fitting secured to the upper end portion or dome of the extinguisher shell, in any manner usual in this art, or other suitable way. As here shown, the outlet fitting passes through the wall of the extinguisher 90 near the mouth thereof, having a flange 24 on the inside, and a nut 25 on the outside, between which the extinguisher shell is clamped. A strainer 26 is mounted on the inner end of the outlet fitting, preferably being detachably screwed thereon. Any suitable character of means may be associated with the outlet fitting to control the diameter and direction of the stream expelled therefrom. 100

That part of the web 21 which is next adjacent to the outlet extends substantially to the mouth ring 3, and is designated by the numeral 21a. It has a sufficient lateral extent to either side from the outlet to exclude immediate discharge of those portions of the solutions which flow through the annular space 22 and the stopper ports at the side next to the outlet, and compel mixing of the solutions before discharge. It serves 110 as a baffle or shield for that purpose. I have found that an angular extent of about 60° of the part 21a around the axis of the extinguisher is sufficient for this purpose. The part 21a is provided with a displaceable segment 27 in its middle portion, such segment being hinged in the manner of a gate and provided with a stop 28 to prevent its swinging outward but adapted to swing inward when the inner receptacle is removed, to give 115 access to the strainer for cleaning or removing it, without requiring removal or displacement of the entire partition 20 for that purpose. Such partition is here shown as being fitted friction tight at its outer rim within the extinguisher shell, and normally immovable. It may be otherwise mounted, however. 120

A tube 29 is secured to the partition 20, preferably well removed from the outlet, and provides a passage for gas from the space 130

30 at one side of the partition to near the bottom of the extinguisher. Said tube is here shown as screwed into a ring or spud 31, which passes through the partition and is secured by threaded collars or nuts 32, 33. A ring 34 surrounds the lower end of the receptacle 5 and carries a collar 35 embracing the tube 29, to center these parts and hold them steady. Arms 36 are connected to this 10 ring and extend outward into connection with sockets 37, attached to the shell of the extinguisher, by which the ring is made secure.

The various parts of the extinguisher may 15 be made of any of the materials usual or suitable for apparatus of this kind, including castings, sheets and tubing of brass, copper, or other suitable material, fabricated in any desired suitable way, the details of which are 20 not important from the standpoint of the protection which I seek, and are well understood by the workers skilled in the art of making such apparatus. I may say, however, 25 as to the inner receptacle, that I prefer to construct the end portion thereof, which includes the shoulder 7, ports 19, and inner lip 9, as a casting, and the balance of sheet metal overlapping and soldered to such casting.

30 It will be understood that when charged and ready for use, the inner receptacle is filled with a solution containing one reagent, and the main body of the extinguisher with a solution containing another reagent which, 35 in reaction with the first reagent, will generate a non-inflammable gas. One reagent may be an acid, or an acid salt, such as aluminum sulphate, and the other a salt of carbonic acid, such as sodium bicarbonate, 40 or a mixture thereof with sodium carbonate. When intended to discharge a lasting foam, a foam stabilizing agent is included in one or both of the charges, preferably the main or larger charge, which contains also the 45 alkaline reagent and is placed in the main body of the extinguisher. The cap 4 is tightly closed, being packed by a gasket 38, if necessary, to prevent evaporation loss and leakage, and the stopper of the inner receptacle is closed by bringing its flange 11 against the lip 9.

In order to use the extinguisher, the stopper is first raised by turning the stem 13, to a greater or less extent, depending on the 50 desired rapidity of mixing of the reagents and discharge of the mixture. Fig. 1 shows the stopper opened to the fullest extent, to obtain the maximum rate of discharge and distance of projection of the foamy liquid. 55 But the extinguisher may be used when the stopper is less widely open and the ports 18 therein more or less obstructed. The entire extinguisher is then inverted, whereupon the liquids flow simultaneously from the inner receptacle through the ports 18 and from

the main body of the extinguisher through the annular passage 22, mingling in the space immediately surrounding the stopper. The restricted annular passage 22 and the separated ports 18 restrict the flow of both solutions and at the same time cause them to be thoroughly and intimately mixed together. Generation of gas commences at once and continues throughout the period of flow. Part of the gas flows through the tube 29 to the inverted bottom of the extinguisher, but without mixing with the liquid in the outer space and being absorbed thereby, and applies pressure on the surface of the liquid in such space. Some of the gas also finds its way through the ports 18, or the spaces between the outer surface of the stopper skirt, the longitudinal ribs 39 on such skirt, and the rim of the lip 9, into the inner receptacle to replace the outflowing solution and apply pressure thereon. The mixture of solutions, carrying the rest of the evolved gas as imprisoned bubbles, is discharged from the outlet under the pressure developed by the evolved gas. The intimate manner in which the mixture of reagents is effected causes simultaneous generation of gas in the locations of all the streams flowing from the ports 18 and uniform gas generation throughout the film flowing through the annular space 22, so that the bubbles of gas are distributed throughout the liquid with a high quality of uniformity as to the size of the bubbles. That is, the bubbles are small and approximate nearly to equality in size. Other things being equal, a foam is more lasting and forms a blanket of more nearly uniform thickness and effectiveness in proportion to the smallness and uniformity of size of the bubbles. The characteristics of the present invention herein described have given remarkable and greatly improved results in this particular.

It will be understood that various changes in structure and arrangement of the various parts of the extinguisher may be made without departing from the invention, within the scope of the appended claims.

The terms used in this specification and in the following claims denoting relative height are to be construed as referring to the apparatus when in the upright position shown in the drawings, except where the context clearly indicates that the inverted position is meant.

What I claim and desire to secure by Letters Patent is:

1. A fire extinguisher comprising a shell having an outlet at one side adjacent to one end, an inner receptacle centrally disposed in said shell and having an outlet near the before named outlet, a partition crossing the shell near the first named outlet and formed to leave an open space contiguous to the inner receptacle near the outlet of the latter,

and a shield extending from said partition to the before named end of the shell at one side of the inner receptacle and between the latter and the first named outlet.

5 2. A fire extinguisher comprising a shell having an outlet from one side adjacent to one end, a partition mounted in said shell extending inward from the walls thereof at a location adjacent to said outlet but at the side thereof away from the above-named end of the shell, said partition having an opening and a web or flange surrounding said opening and extending toward the said end of the shell, that part of said web which lies nearest

10 to the outlet extending substantially to the end of the shell, an inner receptacle passing through the space embraced by said flange and having lateral outlet ports on all sides, said flange being between the first named outlet and the ports at the side adjacent thereto, and a stopper arranged to close off the interior of said receptacle from said ports and being formed with spreading surfaces leading from a central point toward said ports.

15 3. A fire extinguisher comprising a shell having a mouth and an outlet adjacent to said mouth and at one side thereof, a transverse inner partition connected to the walls of the shell and extending inwardly therefrom near one end of the shell but farther distant from the mouth thereof than the outlet, said partition having an interior opening and a web extending from the rim of said opening toward the mouth and between the mouth and the outlet, an inner receptacle extending through said opening in said partition and forming with said web a flow passage of substantially uniform width, said inner receptacle having an outlet in the region of the termination of said web, and means for spreading liquid flowing from the receptacle outlet.

20 4. A fire extinguisher comprising a shell adapted to hold a solution containing one component of a gas forming mixture, a receptacle within the shell adapted to hold another solution containing a complementary gas forming component, the shell having a discharge outlet near one end and the receptacle having an outlet near the same end of the extinguisher, and imperforate separating means extending inward from the shell and between said outlets in position to permit flow of the two solutions into mixture with one another when the extinguisher is inverted and at the same time prevent access of either solution to the first named outlet before mixing of the solutions has occurred.

25 5. A fire extinguisher comprising an outer shell having an outlet adjacent to one end, an inner receptacle having an outlet adjacent to the first named end, and a transverse partition connected at its outer circumference with the walls of said shell dividing the interior of the shell into a mixing space at the

before named end of the shell, from which the shell outlet leads, and a solution containing space further from such end; said partition having an opening larger than the transverse dimensions of said receptacle through which the latter extends and in which it is centrally located, and a flange extending from the rim of said opening toward the before named end of the shell and beyond the outlet from the shell, providing the only flow passage leading from the said solution containing space to the mixing space.

In testimony whereof I have affixed my signature.
